[57] CLAIM

The ornamental design for a fence panel, as shown and described.

DESCRIPTION

FIG. 1 is a front perspective view of the fence panel of the invention (the other side being substantially identical thereto);

FIG. 2 is a top plan view of the fence panel of FIG. 1 (the bottom plan view being substantially identical thereto); FIG. 3 is a front elevational view of the fence panel of FIG. 1;

FIG. 4 is a front perspective view of one side of another embodiment of the fence panel (the other side being substantially identical thereto);

FIG. 5 is a top plan view of the fence panel of FIG. 4 (the bottom plan view being substantially identical thereto); FIG. 6 is a front elevational view of the fence panel of FIG. 4;

FIG. 7 is a front perspective view of one side of a third embodiment of the fence panel (the other side being substantially identical thereto);

FIG. 8 is a top plan view of the fence panel of FIG. 7 (the bottom plan view being substantially identical thereto); FIG. 9 is a front elevational view of the fence panel of FIG. 7;

FIG. 10 is a front perspective view of one side of a fourth embodiment of the fence panel (the other side being substantially identical thereto);

FIG. 11 is a top plan view of the fence panel of FIG. 10 (the bottom plan view being substantially identical thereto); and, FIG. 12 is a front elevational view of the fence panel of FIG. 10.
